(57) **CLAIM**

The ornamental design for a bar cabinet unit, as shown and described.

DESCRIPTION

FIG. 1 is a front elevational view of a bar cabinet unit showing my new design with doors of the bar cabinet unit closed;

FIG. 2 is a front elevational view thereof with the display door of the bar cabinet unit open;

FIG. 3 is a left side elevational view thereof;

FIG. 4 is a right side elevational view thereof;

FIG. 5 is a rear elevational view thereof;

FIG. 6 is an isometric view from one side thereof with all the doors of the bar cabinet unit open;

FIG. 7 is an isometric view from the rear thereof;

FIG. 8 is a front elevational view thereof; and,

FIG. 9 is an isometric view thereof with all the doors of the bar cabinet unit open.

The broken lines are for environmental purposes only and form no part of the claimed design.
